Fred J. Diamant, New York, N. Y., assignor to Desco Shoe Corp., Long Island City, N. Y.

Application January 6, 1953, Serial No. 23,040

Term of patent 7 years

(Cl. D7—7)

To all whom it may concern:

Be it known that I, Fred J. Diamant, a citizen of the United States of America, residing in New York city, county of New York, and State of New York, have invented a new, original, and ornamental Design for a Shoe or the like, of which the following is a specification, reference being had to the accompanying drawing, forming part thereof.

Fig. 1 is a side perspective view of a shoe or the like showing my new design.

Fig. 2 is a perspective view of the opposite side of the shoe from that shown in Fig. 1; and
Fig. 3 is a rear elevational view of the shoe.

I claim:

The ornamental design for a shoe or the like, substantially as shown.

FRED J. DIAMANT.
